[57] CLAIM

The ornamental design for a module cargo unit for a
pickup vehicle, substantially as shown and described.

DESCRIPTION

FIG. 1 is a left side perspective view of a module cargo
unit for a pickup vehicle showing my new design;

FIG. 2 is a rear elevational view thereof;

FIG. 3 is a front elevational view thereof;

FIG. 4 is a right side elevational view thereof;

FIG. 5 is a top plan view thereof; and

FIG. 6 is a bottom plan view thereof.

The broken lines in the drawing are for illustrative
purposes only.
